YARN WINDING

Willis F. Hickes, Snyder, N. Y., assignor to E. I.
du Pont de Nemours & Company, Wilmington,
Del., a corporation of Delaware

Application January 15, 1941, Serial No. 374,453

10 Claims. (Cl. 242—43)

This invention relates to the winding of yarn on to a rotating spool or bobbin to form a cross-wound package. More particularly, it relates to the winding of yarn on a winding apparatus wherein the traversing yarn guide is maintained spaced from the surface of the wind-up package. The invention is particularly applicable to the winding mechanism employed in the manufacture or treatment of artificial filament yarn which is to be wound around a rotating support, for example, in the manufacture of viscose rayon by the bobbin process.

According to the bobbin process for the manufacture of viscose rayon yarn, the freshly formed yarn leaving the spinning bath is collected in package form on a rotating perforated spool or bobbin, the fully wound package being subjected in later operations to treatment with various liquids by pressure or suction means to yield a purified yarn suitable for use in the textile art. It is necessary that the yarn package be uniformly porous and liquid permeable so that this liquid treatment may proceed to a uniform extent and in a rapid and economical manner. To obtain such a package, the industry has utilized a winding apparatus that traverses the yarn along the length of the support bobbin to form a cross-wound package wherein the yarn is wound in a helical manner rather than in the ribbon wind manner typical of the spooling art. Because the freshly formed yarn being wound on to the rotating bobbin is very susceptible to mechanical damage, the traverse guide is generally maintained spaced from the surface of the wind-up package. It is not possible to employ a precision wind apparatus of the type employed when winding the completely finished yarn on to cones or similar types of packages.

Because of this spacing of the guide from the surface of the package, the yarn passing thereto lags behind the guide and is wound on to the bobbin, or other yarn support, at a point some distance behind the momentary position of the guide, this distance being determined by the spacing of the guide from the surface of the package and by the "wind-ratio" employed. This latter term indicates the number of revolutions made by the bobbin for each complete cyclical or back-and-forth movement of the yarn traverse guide. This lag of the yarn behind the guide is of no real significance when the guide is moving along the mid portion of the length of the bobbin package, since the yarn at such a time follows the movement of the guide perfectly and is laid down evenly on the bobbin, although at a distance be-

hind the guide. This lag is of real significance, however, at the moment when the guide reaches the end of each traverse stroke and reverses itself. At such a time the yarn does not follow the movement of the guide perfectly and excess lengths of yarn are laid down on the end portion of the package causing undesirably high shoulder ridges to be formed therein. These shoulder ridges contain more yarn per bobbin surface than does the middle portion of the package, and they are also more dense because they are formed at a moment when the angle of yarn lay-down is changing and the yarn is, therefore, being wound at a very low helical angle. These two effects (uneven cake thickness and denseness) both serve to hinder the subsequent liquid treatment of these end portions of the yarn package and make their purification more difficult.

In previously known winding apparatus, the industry employed a single cam mechanism that imparted a simple harmonic motion to the traverse guide. The yarn packages produced by such a mechanism possessed very large shoulder ridges and were very difficult to purify. To correct this situation, it was proposed to shorten the stroke of the traverse guide to a length less than that of the final package and shift the origin of the traverse stroke along the length of the package by imposing a secondary motion on the stroke of the guide. Thus, a greater proportion of the yarn would be wound into the central portion of the package and the formation of the undesirable shoulder ridges would be avoided. However, the yarn lengths wound on to the package at the reversal points of the guide stroke were still laid down at a low helical angle and the wound packages contained dense portions that impaired their subsequent purification. Furthermore, the mechanism necessary to impart this secondary motion to the traverse guide was expensive to construct and maintain in operating condition.

It has also been suggested heretofore that the traverse cam mechanism be designed to impart an inverse harmonic motion to the traverse guide, whereby the guide would move at a uniform and constant velocity throughout all portions of its stroke save those portions immediately preceding and following each reversal point during which portions the guide moved at a greatly increased velocity. Here too, however, it was necessary to impose a secondary motion on the stroke of the guide in order to form a yarn package free of the undesirable shoulder ridges.

It is an object of this invention to provide an improved traverse mechanism for use with a

winding apparatus wherein the traverse guide is mounted spaced from the surface of the wind-up package, which mechanism will form a yarn package that is eminently suited for subsequent liquid treatment.

It is a further object of this invention to provide an improved traverse mechanism that is adapted to form a satisfactory yarn package with a substantially uniform thickness and density by the use of a single cam.

It is still a further object of this invention to provide a simplified, economical mechanism for winding freshly spun rayon yarn into a package suitable for subsequent liquid purification treatments.

The objects of this invention are accomplished, in general, by a winding apparatus wherein the traverse movement of the yarn traverse guide is carried out by means of a traverse mechanism utilizing a single, rotating cam provided with the necessary followers and lever arrangements for the purpose of forming a cake of substantially uniform thickness and density. The cam is so designed that the traverse guide is moved with a uniform velocity throughout its entire stroke in either direction except for a short period immediately following each reversal, during which period the said guide is moved at a higher velocity. By virtue of this short rapid movement of higher velocity immediately after each reversal, the guide is able to overcome the effect of yarn lag that normally occurs at these reversal points and thus prevent the formation of undesirably high ridges in the shoulder portions of the yarn package.

The following description of the invention will be more readily understood if taken in connection with the accompanying drawings, wherein:

Figures 1, 2, and 3 are surface developments of one extreme end of a bobbin showing the movement of the traverse guide and the thread lay-down on the developed surface of the bobbin, when the traverse guide is spaced from the bobbin, under different conditions of yarn traverse.

Figure 4 is a diagrammatic side elevational view showing an apparatus for the winding of a freshly spun yarn on a bobbin.

Figure 5 is a front elevational view of a yarn winding apparatus constructed in accordance with the elemental features of the present invention.

Figure 6 is an enlarged front elevational view of a plate cam suitable for use in the present invention.

Figure 7 is a graphic illustration showing the basic elements of yarn traverse in accordance with the present invention.

Figure 8 is a diagrammatic front elevational view, with the bobbin in section, of the improved yarn package formation obtained by use of the present invention.

Figure 9 is a side elevational view, with parts shown in section, of a modified form of yarn traversing mechanism.

Figure 10 is a front elevational view taken along the line 10-10 of Figure 9.

Figure 1 of the drawings illustrates by surface development of one extreme end of the bobbin, the line of yarn lay-down and the path of movement of a traverse guide when using a traverse guide spaced from the bobbin and having a uniform speed traverse motion over its entire length of traverse. The line A-A¹ designates the line of yarn lay-down on one extreme circumferential

end of the bobbin. The line A-B-B¹ designates the path of movement of the traverse guide at the extreme circumferential end of the bobbin. It will be noted that the yarn lay-down lags 5 behind the path of travel of the traverse guide. When the traverse guide is at point B-1, the yarn will be laid down on the bobbin at the point A-1. As the traverse guide moves from B-1 to B-2, B-3 . . . B-13, the yarn is laid down on 10 the end of the bobbin at the corresponding points A-1, A-2, A-3 . . . A-13. The numbers referred to in the drawings, both as to yarn lay-down and traverse guide movement, designate equal increments of time. Thus, as the travel 15 of the traverse guide reverses at the point B the yarn is laid down on the bobbin over a low helix angle. As a consequence, more yarn, per bobbin surface, will be laid down on the end of the bobbin than on other sections of the bobbin resulting in high shoulder ridges at the two extreme ends of the package.

Figure 2 illustrates, by similar surface development of one extreme end of the bobbin, the theoretical yarn lay-down in an ideal situation (unobtainable) where the traverse guide moves to one extreme position B of its traverse stroke and then, after reversal, instantaneously moves from the point B to the point B¹. Under such ideal conditions, the thread would have a sharp 25 change in direction at the point A, A¹. Thus, if such an ideal situation were possible, a package would be formed having straight-sided ends and having a uniform thickness and density throughout.

Figure 3 of the drawings is another similar surface development of one extreme end of the bobbin showing the line of yarn lay-down and the path of movement of a traverse guide when using a traverse movement which is uniform throughout its entire traverse stroke except for an increased traverse speed over a short distance of the length of its traverse strokes beginning immediately after reversal of direction. Under this situation the ideal situation referred to in Figure 2 is closely approached. As will be noted by the line A-B, the traverse arm moves in a uniform direction to one extreme end B of its stroke, and then the speed of traverse is increased, as illustrated over the time increments

40 B¹, B², B³, and B⁴. As a result, the yarn lay-down changes direction much more quickly than in the case of a traverse movement as illustrated in Figure 1. As a result, the yarn can be laid down on the package with a slightly rounded end but 45 with a uniform thickness and density as hereinafter referred to with reference to Figure 8 of the drawings.

Referring to Figure 4 of the drawings, the yarn 50 formed by the extrusion of a spinning solution into a spinning bath contained in trough 2 is led through the bath for a suitable distance by guide 3, and is then passed upwardly to the rotating bobbin 4. The yarn is traversed back and forth across the face of the bobbin by the 55 oscillating traverse guide 5 so as to form the desired yarn package 6. As shown in the drawings the guide 5 is so mounted on the lower end of the oscillating arm 10 that it is spaced from the surface of the bobbin by the distance X. The 60 traverse arm is oscillated by means of oscillating horizontal rod 11 which is fixedly attached to the arm 10. The rod 11 is supported in bearings 12 and is caused to oscillate through a small arc by means of a cam mechanism contained in 65 compartment 31. The rod 11 and the arm 10 are 70 75

oscillated over an arc which will be sufficient to move the yarn along the desired length of traverse across the face of bobbin 4.

Figure 5 illustrates a cam mechanism which will impart the desired oscillation to the rod 11 and arm 10 to obtain a package of substantially uniform thickness and density by the use of a single cam. The cam mechanism comprises a plate cam 20 of non-symmetrical but constant diameter outline. The cam surface is provided with two sets of oppositely disposed slopes whereby to impart to member 23 through cam followers 22-22 a reciprocating motion of substantially uniform speed in one direction, then immediately after reversal of direction an increased speed in the opposite direction followed by a substantially uniform speed in the same direction, then immediately after again reversing the direction an increased speed in the first-named direction followed by the first-named movement; the two lower speeds being substantially uniform and equal, and over the major portion of the travel of the member 23, the two higher speeds also being substantially uniform and equal but over a minor portion of the travel of the member 23. The member 23 is provided with slots 24 and guide pins 25 whereby to maintain the same in vertical reciprocation. The member 23 is also provided with a slot 27 in which may be positioned guide pin 28 for the oscillation of arm 26 which is fixedly attached to rod 11, and imparts to the latter an oscillating motion. Figure 5 shows the member 23 in its extreme top position whereby the arm 26 is raised to its extreme position and the arm 10 in its extreme right-hand position.

By rotating the cam 20 in the direction of the arrow about the cam shaft 21, the cam followers 22-22, which are attached to the member 23, will be made to follow the cam outline and reciprocate the member 23 in the following manner: First, with a relatively high speed in a downward direction over a short length of its travel, then with a relatively slow speed in the downward direction over the major portion of its travel, then with a relatively high speed, substantially equal to the first-named high speed, in an upward direction over a minor portion of its travel, and then with a relatively slow speed, substantially equal to the first-named slow speed, in an upward direction over the major portion of its travel.

Referring to Figure 6 of the drawings, the cam 20 is shown with more particularity. The line numbered 1-3 is drawn through the two oppositely disposed points of reversal of direction of the cam surface. The line numbered 2-4 is drawn into the points of speed change; or of cam surface slope change. The two lines divide the cam surface through four sections, A, B, C, and D. The cam surface slope of section A is substantially equal and opposite to the cam slope of section C and the cam slope of section B is substantially equal and opposite to the cam slope of section D. As a result, as the cam followers move over the slopes of the cam surface, the above-mentioned alternate speeds will be imparted thereto. Preferably, each of the high speed sections A and C of cam 20 cover not to exceed 30° of the cam surface. Consequently, the high speed of traverse of member 23 immediately after reversal will take place not to exceed over $\frac{1}{6}$ of its travel. In order to obtain substantially uniform reciprocal motion from a uniform rotary motion of the cam, the curved

surfaces of the cam will be drawn along the lines of a spiral of Archimedes.

The sections of the cam surface which impart the higher speed to the cam followers are preferably so sloped that the speed of the cam followers will be at least 20% faster than the speed imparted thereto by the lower speed sections of the cam. With a wind ratio of approximately 4 and a spacing between the traverse guide and the bobbin of approximately $\frac{1}{2}$ inch, it is preferred that the speed of the follower as it travels over the high speed sections of the cam is at least 50% higher than the speed of the follower as it travels over the slow speed sections of the cam. It will be noted that the cam surface at the two points of juncture of line 1-3, the points of reversal of direction of the cam follower, are curved instead of sharply outlined. As a result, the reversal of direction, although not instantaneous, will be as nearly instantaneous as is consistent with operability of the cam mechanism from a maintenance standpoint.

Figure 7 of the drawings illustrates graphically the nature of the movement imparted to the traverse guide 5 during the complete rotational movement of the cam 20. The line 101 illustrates the uniform movement of the traverse guide 5 in one direction to an extreme position of its movement 103. After reversal of direction, the speed of the traverse guide 5 is increased as illustrated by the short line 104 after moving approximately 0.1 of its stroke. The movement of the traverse guide is then continued in the same direction, as illustrated by line 105, but at a speed approximately the same as that illustrated by line 101. This speed and direction is maintained to the opposite extreme end of its stroke after reversal at point 106. The traverse guide is moved in the opposite direction, as illustrated by line 107, but at the same speed as illustrated by line 104. As illustrated by second line 101, the original speed and direction is then again resumed by the traverse guide.

Figure 8 of the drawings illustrates by dotted line 150 the approximate contour of a cake wound by the use of a traverse guide moving at a uniform speed throughout its traverse stroke cycle, when the traverse guide is spaced from the bobbin. The full line 160 illustrates the general contour of a yarn package wound in accordance with the present invention.

Figures 9 and 10 of the drawings illustrate a modified form of apparatus to be used when difficulty is encountered by too frequent coincidence of succeeding thread layers sometimes referred to as "ribbon winding." In this modification an eccentric is positioned to rotate within the traverse guide reciprocating cam. The modified apparatus comprises a reciprocating member 50 provided with a guide slot 52 and guide pin 56, the guide slot and pin maintaining the member 50, in a substantial reciprocating movement. The member 50 is also provided with a slot 54 in which the guide pin 58 attached to the oscillating arm 26 is positioned. The cam followers 60-60 are attached to the reciprocating member 50. These cam followers are adapted to follow the cam surface of a plate cam 62. A rotating eccentric member 64 is positioned in crosshead 86 which in turn is positioned within slot 88 in the member 59. The gear 69 is rotated by means of drive shaft 68. The gear 69 rotates gear 70 which in turn rotates the shaft 66. The shaft 66 is freely rotatably mounted within eccentric 64 and is provided with a gear wheel 76 which

is made to rotate gear 78 mounted on stub shaft 80. Gear 82, which is also keyed to stub shaft 80, rotates gear 84 which is integral with eccentric 64. The rotation of the eccentric within the crosshead 86 causes a slight movement to be imparted to reciprocating member 50. The cam 62 is rotated by means of pin 74 mounted within the boss 72 integral with gear wheel 70. The eccentric movement of the cam will be superimposed upon the movement imparted to member 50 by cam 62, and since the cam and eccentric are rotated at different speeds the yarn helices on the bobbin will be spaced from each other without identical repetition except for possibly widely spaced intervals.

In the detailed apparatus above described, the traverse motion was imparted to the traverse guide by means of a plate cam in cooperation with connecting linkage mechanism. Obviously, a similar motion can be imparted to the traverse arm by the use of a suitable connecting linkage and a grooved cam. The cam specifically described in the drawings is provided with two sections having a relatively high slope and two sections with a relatively low slope (high speed and low speed sections). Obviously, a cam may have four high slope sections and four low slope sections, it being only necessary that each high slope section have a substantially equal and oppositely sloped high slope section, and each low slope section have an equal and oppositely sloped low slope section, and that the low slope sections alternate with the high slope sections.

From the above description it will be clear that the applicant obtains a package of uniform thickness and density with a winding apparatus in which the traverse guide is spaced from the rotating yarn support, by means of a single cam which imparts to the traverse guide a relatively slow motion in one direction to its extreme position, then a reversal of direction, then a relatively fast motion in the opposite direction, then a continuation of movement in the same direction but at the slow motion above referred to. This last-named slow motion is continued to the opposite extreme position of its traverse then a reversal of direction, then at a relatively fast movement in the opposite direction, and then a resumption of the slow motion first referred to. The relatively slow movement of the traverse guide will take place over the major portion of its traverse stroke.

This invention provides a means of eliminating a large portion of the thread lag occurring at the reversal points of the traverse stroke of a winding machine wherein the traverse guide is mounted spaced from the surface of the wind-up package whereby the build-up of excessive amounts of yarn at the shoulder portions of the package is avoided.

The invention provides a means whereby a single primary cam can be used to actuate the traverse guide of the winding mechanism to form a yarn package of substantially uniform thickness and density.

The apparatus provided by the invention is simple to construct and economical to maintain in operating condition.

The invention provides a means of forming a uniformly porous and liquid permeable yarn package on a winding machine wherein the thread guide is mounted spaced at a distance from the surface of the winding package.

The invention has been discussed in connection with the winding mechanism of a rayon yarn

spinning machine. However, the invention is not limited to use with such a machine, but is applicable to all types of winding mechanisms wherein the traverse guide is mounted spaced from the surface of the wind-up package.

5 Since it is obvious that many changes and modifications can be made in the details above described without departing from the nature and spirit of the invention, it is to be understood that 10 the present invention is not to be limited to the said details except as set forth in the appended claims.

I claim:

1. The method of winding yarn on a rotating 15 yarn support which comprises traversing the yarn with predetermined strokes in back and forth directions across the face of the support as the yarn is wound thereon, a minor fraction of the length of the first portion of the traverse strokes in each direction of traverse being carried out at a higher speed than the remaining portion of said strokes.

2. The method of winding yarn on a rotating 20 yarn support which comprises traversing the yarn with predetermined strokes in back and forth directions across the face of the support as the yarn is wound thereon, a minor fraction of the length of the first portion of the traverse strokes in each direction of traverse being carried out at a higher speed than the remaining portion of said strokes, said remaining portion of said strokes being carried out at a substantially uniform speed.

3. The method of winding yarn on a rotating 25 yarn support which comprises traversing the yarn with predetermined strokes in back and forth directions across the face of the support as the yarn is wound thereon, a minor fraction of the length of the first portion of the traverse strokes in each direction of traverse being carried out at a higher speed than the remaining portion of said strokes, the higher speed portion of the strokes being carried out at a substantially uniform speed, and said remaining portion of said 30 strokes also being carried out at a substantially uniform speed.

4. The method of winding yarn on a rotating 35 yarn support which comprises traversing the yarn with predetermined strokes in back and forth directions across the face of the support as the yarn is wound thereon, a minor fraction of the length of the first portion of the traverse 40 strokes in each direction of traverse being carried out at a higher speed than the remaining portion of said strokes, the higher speed portion of the strokes being carried out at a substantially uniform speed, and said remaining portion of said 45 strokes also being carried out at a substantially uniform speed.

5. In an apparatus for winding yarn, a rotating 50 yarn support, a traverse arm including a traverse guide for traversing the yarn in back and forth directions across the face of said rotating support, said traverse arm spaced from said support, a cam, a cam follower connected to said traverse arm, said cam adapted to impart to said traverse arm, movements of substantially uniform speed over the major portion of its traverse strokes to 55 extreme positions in opposite directions, followed by movements, immediately after reversal of direction, over a minor portion of its traverse strokes at a higher speed.

6. In an apparatus for winding yarn, a rotating 60 yarn support, a traverse arm including a traverse guide for traversing the yarn in back and forth directions across the face of said rotating support, said traverse arm spaced from said support, a cam, a cam follower connected to said traverse arm, said cam adapted to impart to said traverse 65 arm, movements of substantially uniform speed over the major portion of its traverse strokes to extreme positions in opposite directions, followed by movements, immediately after reversal of direction, over a minor portion of its traverse strokes at a higher speed.

7. In an apparatus for winding yarn, a rotating 70 yarn support, a traverse arm including a traverse guide for traversing the yarn in back and forth directions across the face of said rotating support, said traverse arm spaced from said support, a cam, a cam follower connected to said traverse arm, said cam adapted to impart to said traverse 75 arm, movements of substantially uniform speed over the major portion of its traverse strokes to extreme positions in opposite directions, followed by movements, immediately after reversal of direction, over a minor portion of its traverse strokes at a higher speed.

arm, movements of substantially uniform speed over the major portion of its traverse strokes to extreme positions in opposite directions, followed by movements, immediately after reversal of direction, over a minor portion of its traverse strokes at a substantially uniform and higher speed.

7. In an apparatus for winding yarn as defined in claim 5 in which the cam is a plate cam.

8. In an apparatus for winding yarn, a rotating yarn support, a traverse arm including a traverse guide for traversing the yarn in back and forth directions across the face of said rotating support, a cam, the cam surface of which has a section of uniform slope to one extreme followed by a second section of uniform slope greater than said first-named slope in the opposite direction, followed by a third section having a uniform slope of equal degree to said first-named slope to an opposite extreme in the direction of said second-named section, followed by a fourth section having a uniform slope of equal degree to

5 said second-named section but in the direction of said first-named section, followed by a section identical with said first-named section, a cam follower connected to said traverse arm, said cam adapted to impart to said traverse arm movements of substantially uniform speed over the major portion of its traverse strokes to extreme positions in opposite directions, followed by movements, immediately after reversal of direction, over a minor portion of its traverse strokes at a higher speed.

10 9. A wound yarn package the end portions of which are comprised of yarn windings in which successive windings are alternately quick-traverse and slow-traverse windings.

15 10. A wound yarn package having slightly rounded end portions, said end portions comprised of yarn windings in which successive windings are alternately quick-traverse and slow-traverse windings.

20 WILLIS F. HICKES.
